71 Claims. (Cl. 12—37)

This invention relates to sole pressing machines and particularly, though not exclusively, to machines for conforming outsoles to shoe bottoms.

5 Sole laying machines are used at the present time in the boot and shoe industry for pressing a sole against the bottom of a boot or shoe (to which it is usually subsequently to be permanently secured) in order to cause the sole to conform closely to the curves of the boot or shoe bottom. In using a sole-laying machine in making welted shoes and usually too when making McKay sewed shoes, an adhesive is present and the pressing not only shapes the sole but sticks it in place. Sometimes, however, in making McKay sewed shoes the sole has been tacked in position beforehand on the shoe bottom in one or two places and the machine merely molds the sole. In making some classes of shoes such a machine is used not merely to cement the sole in position temporarily but to effect permanent bottoming, a suitable cement for the purpose being then used.

Objects of this invention are to provide an improved machine for work of the general nature indicated in the operation of which the operator will not have to wait for the operation of the machine but can work to his full capacity, and to provide a machine in which the work is presented to the operator in position for convenient inspection of the work which is being placed in the machine and in which the work may be clamped in the machine under preliminary pressure with a minimum of manipulation of parts.

25 To these ends the illustrated machine comprises a number of pressing units arranged on a carrier or turret movable to present the units successively in work receiving and work discharging position, and pressure applying means operating while each unit is in said position and independent of movement of the carrier for applying pressure to that unit and relieving pressure simultaneously from another unit, preferably from the unit which is next to be brought into work discharging and work receiving position by movement of the carrier. In the illustrated machine each pressing unit comprises a shoe holding device and a sole engaging pad adapted to be dilated by fluid pressure to apply 50 pressure to the shoe bottom while the pad is in shoe receiving position. As illustrated, the shoe engaging pads are arranged on the periphery of a turret or table arranged for rotation in a horizontal plane and are inclined downwardly and 55 outwardly of the turret to facilitate the inspec-

tion of a shoe and sole placed thereon while the sole and shoe are being located relatively to each other and while pressure is being applied to the sole. In the illustrated machine the pads are distorted to apply pressure to the shoe by air pressure which is supplied to each pad in turn through a valve located centrally of the turret which valve is caused to be turned at the will of the operator, in a direction opposite to the direction of rotation of the turret by previously stored power, for example, by a tension spring, to admit air to that one of the pads which is in work receiving position. Preferably and as illustrated, the valve simultaneously relieves pressure from the pad next to the pad that is being filled. In the illustrated machine, power-operated means, preferably pneumatic, is provided for rotating the turret and for storing energy to operate the valve reversely. During rotation of the turret the supply of air to the pad just filled and the exhaustion of air from the pad next to be filled are maintained.

For clamping a shoe on a pad, the illustrated machine is provided with novel shoe holding and pad supporting means. A three-point bearing for each pad support is provided, two of the points being spaced laterally of the pad beneath its longitudinal central portion and the bearing at the third point being yielding and located near the toe end of the pad support to permit longitudinal tipping of the pad support. As illustrated, the central bearings are relatively adjustable to enable the pad support to be tipped laterally.

The shoe holding means, as illustrated, comprises an arm pivoted near the toe end of the pad and provided with a spring for raising it from the shoe, said arm being provided with a toe rest having a rubber roll having an axis extending across the forepart of the shoe substantially perpendicular to the longitudinal median line of the forepart and a short last pin for engaging the pin hole of the last. For clamping the arm against the shoe the illustrated machine provides for each pad a bail pivoted to the pad support substantially at its longitudinal center and extending over the arm of the shoe holding device, the upper surface of the arm being so shaped that by movement of the bail toward the heel end of the shoe the arm will press the shoe upon the pad with preliminary pressure.

In order to press the shank portion of the sole tightly against the shoe, particularly in the case of high-arched shoes, each of the sole pads may, as illustrated, be provided with a separate shank or waist pad, preferably of rubber, the upper

105

110

surface of which is shaped to conform to the longitudinal and transverse contour of the shank portion of the shoe. Each shank or waist pad is preferably linked to its sole pad so that it will be held in proper position on the sole pad and may be swung out of operative position when its use is not desired.

The various objects and the several features of the present invention will become more evident from the following description, with reference to the accompanying drawing, of an illustrative machine in which the several features of the present invention are embodied in convenient forms.

15 In the drawing.

Fig. 1 is a side elevation, partly in section, showing sufficient of the head of the illustrative machine to enable the invention to be clearly understood;

20 Fig. 2 shows a side view of a valve hereinafter described detached from the machine;

Fig. 3 is a sectional plan view of the valve showing also a valve casing surrounding the valve;

25 Fig. 4 is a side elevation looking from the left of Fig. 1 and showing certain details hereinafter described; and

Fig. 5 is a sectional detail on the line V—V of parts shown in Fig. 1.

The illustrative machine for pressing and shaping soles to shoe bottoms comprises a vertical column 10 adapted to stand on the floor and adapted to support a horizontal turret 12 at its upper end. For this purpose there is spaced above the upper end of the column a horizontal cross-bar 14 which is joined to the column 10 by vertical members 16, 18. The cross-bar 14 has a circular face 20 formed on its upper surface on which the turret 12 rests and rotates. The turret 12 has a hollow substantially cylindrical neck 22 arranged centrally thereof which projects vertically upward from the turret. A vertical shaft-like member 24 (hereinafter termed the valve) is housed in bearings 26 in the hollow cylindrical neck 22 and passes at its lower end through a bearing in the cross-bar 14 and into a vertical bore 28 in the upper end of the column 10. By this means the turret 12 is maintained central relatively to the column 10.

The turret 12 of the illustrative machine is provided with six shoe-holding devices indicated generally at 30 and six hollow pads 32, which latter are adapted to be dilated by fluid pressure to press soles against the bottoms of shoes held in the shoe-holding devices. The shoe-holding devices 30 are arranged one above each of the pads 32 on the turret 12. The pads 32 are arranged radially of the turret 12 and are spaced equally apart around the periphery of the turret and each pad is supported on a self-adjusting bed 34. Each bed comprises a metal plate substantially longer and wider than a shoe and has two holes 36 drilled partly into it from its under side, one on each side of the bed and about half way along the length of the bed. Supporting stems 38 project upwardly an adjustable amount through the outer ends of bosses 40 on the periphery of the turret 12 and engage in the holes 36 aforesaid in the bed 34, the holes being of greater diameter than the stems 38 to allow the bed to tilt somewhat on the ends of the stems in a plane radial to the turret. The said stems are threaded into said bosses and are independently adjustable heightwise by rotation thereof so that the bed may be adjusted laterally of the plane of the turret. Near its inner end each bed 34 is provided

on its under side and midway of its width with a lug 42 to which is pivoted the upper bifurcated end 44 of a depending rod 46. This rod 46 passes through a bearing 48 in the turret 12 and has a nut 50 on its lower end. Springs 52, 54 are provided which encircle the rod 46 above and below the turret 12, one of the springs 52 resting at its lower end upon the turret 12 and at its upper end upon the bifurcated end 44 at the top of the rod 46, while the other 54 rests at its lower end upon the nut 50 at the lower end of the rod 46 and at its upper end against the turret 12. Thus it will be seen that each pad supporting bed 34 is mounted upon a three-point bearing, two of the bearing points being located midway of the length of the bed and the third being yieldingly mounted near the inner end thereof. This permits each bed to rock on its supporting stems in a vertical plane against the action of the springs 52, 54 surrounding the depending rod 46 near the inner end of the bed 34. The arrangement is such that when the beds are in normal position upon the machine they are inclined upwardly toward their inner ends at an angle of about twenty degrees to the horizontal for the outer half of their length while the inner half (which is bent upwardly and inwardly of the machine) has an upward inclination of some thirty-five degrees to the horizontal.

Each pad 32, which preferably is pneumatic, is of a length and width similar to that of the bed 34 and comprises a rubber bag enclosed in a casing of leather. The upper side of the leather casing preferably comprises two layers of leather superimposed one on the other in order to protect the rubber bag against puncturing. An air inlet pipe 56 (of which the machine is provided with six, one for each pad but of which only one is shown in the drawing) is screwed to a union 58 which is in turn secured to the rubber bag 32. In order to avoid confusion of the drawing the air inlet pipe 56 to the left-hand pad in Fig. 1 is not shown but the supporting members for the right-hand pad are omitted to show the air inlet pipe to that pad. The union 58 passes downwardly through a hole arranged centrally of the bed 34 and is clamped thereto by nuts 60 on the upper and lower sides of the bed.

In order to hold a shoe 62 in fixed relation to a pad 32 while air is admitted to the latter to cause it to press against a sole 64 to lay it against the shoe, the illustrated machine is provided with the shoe holding devices 30 aforesaid which are positioned one above each pad and which can be lowered toward the pads independently of each other. For this purpose the substantially cylindrical neck 22 on the turret 12 is provided near its upper end with six pairs of ears 66, one pair being situated above each of the pneumatic pads. A shoe supporting arm 68 is mounted in each pair of vertical ears 66 and is held therein by means of a horizontal pivot pin 70 passing through the ears 66. Each arm 68 may be swung downwardly about its pivot in a plane radial to the turret 12 from a raised position into a substantially horizontal position and when in such position it overlies the median line of the pneumatic pad 32 beneath it and the arm is of such a length that its outer free end lies practically vertically above the outer end of the pad carrying bed 34. A coil spring 72 provided around the pivot 70 of each arm 68 tends to raise the arm from the said horizontal position in order to allow of easy access to the pneumatic pad 32. Near the lower side of the outer end of each arm 68 there is a slot 74 about an inch and a half long running in such a

direction that when the arm is in its substantially horizontal position the slot 74 is approximately parallel to the outer end of its respective pad carrying bed 34. The lower edge 76 of the arm 68 lying beneath the slot 74 is parallel therewith. A last-pin carrier 78 is mounted on the arm 68 near the outer end thereof and is freely movable along it to an extent limited by the length of the slot in order to allow a last pin 80 to engage in lasts of different sizes. The last pin carrier 78 is U-shaped at its upper end and embraces more or less closely the opposite sides of the arm 68 and lies close to and is guided in its movement of adjustment by the lower edge of the arm. A cross-pin 82 passing through the U-shaped portion of the last pin carrier 78 and the slot 74 in the outer end of the arm 68 serves to retain the last pin carrier in the position described while leaving it free when not in engagement with a last to travel to and fro along the arm 68 to the extent prescribed by the slot 74. The last pin 80 comprises a short conical peg which projects downwardly and when the arm 68 overlies the pad is perpendicular to the downwardly inclined rear part of the pad supporting bed 34. The last pin 80 is held in the last pin carrier 78 and is adapted to enter loosely part way into the last pin hole in the heel end of a last, the under side of the carrier 78 being adapted to bear on the crown of the last. About half way between its inner and outer ends each arm 68 is provided with a second slot 84 lying above the inner part of its respective pad 32 and parallel to the slot 74. That part 86 of the under side of each arm lying beneath the slot 84 is formed parallel therewith. A U-shaped block 88 is mounted to embrace the arm 68 on opposite sides of the slot 84 in a manner similar to the mounting for the last pin carrier 78 and it may be clamped in adjusted position along the arm 68 by a thumb-screw 90. The U-shaped block 88 carries a substantially cylindrical rubber pressure roll 92 which is adapted to rest upon and press just behind the toe against the upper side of a last which is positioned beneath the arm 68 by engagement of the conical last pin 80 in the last pin hole at the heel end of the last. The U-shaped block 88 has an ear 94 depending downwardly therefrom at each side of the roll 92 and these ears are twisted slightly out of parallelism with the arm 68, as shown in Fig. 1. A spindle 96 passing through the ears 94 provides a horizontal axis for the pressure roll 92, and owing to the twisted arrangement of the ears 94 on their carrying block 88 the axis of the pressure roll 92 is inclined out of perpendicularity with the arm 68 so that the roll 92 will lie more or less perpendicularly of the median line of the forepart of the last which lies directly beneath the arm 68. This arrangement provides for an effective distribution of pressure on the forepart of the last in spite of the "swing" of the last. The twist of the pressure rolls on neighboring arms is reversed relative to those arms so that right and left shoes may be dealt with at alternate stations.

Mounted on coaxial horizontal pivots 98 at its lower end beneath each pad supporting bed 34 is an upstanding stirrup 100 the cross portion at the upper end of which is adapted to extend horizontally across the upper edge of the shoe supporting arm 68 and perpendicularly of said arm. The horizontal pivots 98 for each stirrup are positioned to lie approximately beneath the middle of the arm when the arm occupies a substantially horizontal position. The said horizontal pivots 98 are carried in bearings formed in the outer end of the bosses 40 before mentioned as having the said stems 38 secured therein and the axis of said pivots 98 passes perpendicularly through the axis of the pair of stems 38. When the arm 68 is to be allowed to assume the raised position to which it is urged by the coil spring 72, the upper end of the stirrup 100 is moved to a position in which it lies more or less over the pivot 70 for the arm 68 and is supported in this position by a lug 102 projecting upwardly from the edge of the arm 68. The upper edge of the arm 68 is cam shaped (i. e., is eccentric to the pivots for the stirrup 100) so that when the stirrup is swung outwardly its cross portion bears with increasing pressure upon the upper edge of the arm and forces the arm downwardly into its horizontal position, the stirrup remaining locked by the pressure between it and the arm wherever it is placed along the arm and thus holding the shoe upon the pad under preliminary pressure. The arm 68 may, however, be swung downwardly with one hand to quicken the operation and the stirrup 100 may be swung into its forward position over the arm with the other hand when the arm has been caused to occupy its horizontal position. This arrangement is found to allow of a very quick and simple work jacking or unjacking operation. The disposition aforementioned of the stirrup pivots 98 in relation to the stems 38 is such that the pressure of the sole laying which is taken by the stirrup is transmitted more or less directly by the pivots 98 to the said stems 38 and thus to the bed 34 or at all events practically only the outer end of the said boss 40 participates in the application of pressure, the bosses which constitute the only positive connection of the bed 34 with the machine column 10 serving little purpose beyond that of carrying the weight of the associated parts. The stirrup 100, swinging as it does, to 115 operative position from a position over the toe of the shoe toward the middle of the latter instead of from a position over the heel end toward the middle of the shoe, renders the jacking of even high topped shoes by it an easy matter.

From the description so far given it will be understood that the illustrative machine has six sole laying stations, that the operating mechanism at each station comprises a pneumatic pad supported upon a self-adjustable or compensating bed, and that a shoe supporting arm can be swung downwardly over each pad to hold down against the pressure of the pad a last carrying a shoe for the sole pressing operation.

The pneumatic pads 32 are adapted to be inflated and deflated at certain times by mechanism now to be described. The air inlet pipe 56 for each pad passes from its connection with the union 58 at the under side of its bed 34 upwardly to a valve casing 104 which is carried on the top of the upstanding neck 22 on the turret 12, and the pipe 56 has sufficient flexibility to allow of the tilting of the union 58 as the bed 34 tilts. This valve casing 104 is of frusto-conical shape (its smaller end being at the top) and is adapted to fit over and surround closely a frusto-conical part 106 at the top of the valve 24. The valve casing 104 is connected to the neck 22 of the turret 12 by three horizontal lugs 108 (of which only one is shown) through which pass upstanding pins 110 secured to the upper face of the upstanding neck 22, and springs 112 confined between washers 114 at the tops of the pins 110 and the lugs 108 serve to urge the valve casing 104 downwardly to fit closely around the frusto-

conical part 106 of the valve 24. Each of the six inlet pipes 56 leading to the pneumatic pads 32 is connected by means of a screw union 116 with an inlet port 118 passing radially through the valve casing and the six inlet ports 118 are arranged equidistantly around the latter, i. e., at sixty degrees apart and in the same horizontal plane. The central shaft-like member forming the valve 24 is provided with a central vertical duct 120 which is connected at its upper end by means of a flexible pipe 113 (preferably provided with a cock) to a source of compressed air (not shown).

This central duct 120 is closed at its lower end, and near to the upper end of the valve 24 and on a level with the inlet ports 118 in the valve casing 104 is a single supply passage 122 (see Figs. 2 and 3) running radially of the valve 24 from the central duct 120 and leading at its outer end into one end of a semi-circular groove 124 which runs horizontally around the valve 24 for approximately thirty degrees. The valve 24 has also formed in it a horizontal radial exhaust passage 126 the axis of which is arranged at thirty degrees away from the axis of the supply passage viewed in plan (Fig. 3) and at some sixty degrees away from the further end of the groove 124 aforesaid and is also on the same level as the inlet ports 118 in the valve casing 104. The exhaust passage 126 proceeds inwardly radially of the valve 24 for a short distance and communicates at its inner end with a vertical exhaust pipe 128 (see Figs. 1 and 2) fitting in a groove 130 (Fig. 3) sunk into the peripheral face of the valve 24 leading to the lower end thereof. The valve 24 is adapted to be rotated at certain times in the neck 22 of the turret 12 (and therefore in the valve casing 104) in one direction to cause the supply and exhaust passages to come into alignment with the inlet ports 118 of those adjacent pads which occupy certain positions hereinafter stated.

At certain other times the valve 24 and turret 12 are caused to rotate together in the opposite direction as hereinafter described. For this purpose there is secured to the valve 24 near its lower end between the top of the machine column 10 and the cross-bar 14 aforesaid an arm 132 which projects radially and horizontally from the valve 24. This arm 132 carries, about half way along its length, a vertical plunger 134 (see Figs. 1 and 4) which is housed in a bearing 136 in the arm 132 and which is urged upwardly in its bearing by means of a spring 138 housed within in the plunger 134 and bearing at its lower end upon a fixed cross-pin 140 secured to the arm 132. The lower end of the plunger 134 projects below the arm 132 and is formed with a head 142 by which the plunger may be pulled downwardly, as hereinafter explained. The upper end of the plunger 134 projects above the arm 132 a substantial amount and a horizontal piston rod 144 has at one end a vertical bore in which the upper end of the plunger 134 is received and beyond which it projects upwardly. The other end of the piston rod 144 is formed as a piston 146 which is received within a horizontal cylinder 148 and compressed air may be admitted to this cylinder behind the piston 146 at certain times, as hereinafter explained, to cause the piston rod 144 to reciprocate in one direction and thereby to rotate, in a clockwise direction as seen from above, the arm 132 and the valve 24 and, through means hereinafter described, the turret 12.

75 A spring 150 is secured at one end to the arm

132 and at its other end to the machine frame and serves to rotate the arm 132 and valve 24 in the opposite direction when allowed to do so. The cylinder 148 is mounted, at that end remote from the arm 132 (i. e., its closed end) on a vertical pivot 152 secured to a bracket 154 on the machine frame so that the cylinder 148 may oscillate slightly in a horizontal plane to allow the outer end of the piston rod 144 to follow the rotary movements of the arm 132. A flexible pipe line 156 is connected at one end to the cylinder 148 close to the back of the cylinder and at the other end the pipe line is connected to a ring 158 which is secured to the lower end of the valve 24 so as to rotate with it and has a radial passage through it in communication with the central duct 120 in the valve 24. A slide valve 160 carried by the said ring 158 and interposed between the ring and the pipe line 156 puts the pipe line into communication at certain times with the central duct 120 aforesaid. Interposed between the lower end of the neck 22 of the turret 12 and the face 20 on the cross-bar 14 on which it rests, is a horizontal ratchet wheel 162 which is secured to the turret 12 and which surrounds the central valve 24. This ratchet wheel 162 is provided with six holes 164 spaced equally apart around its periphery and at a radial distance from the central valve 24 equal to that of the plunger 134. The upper end of the plunger is adapted at certain times to enter into one or other of the holes 164 in the ratchet wheel 162 and for that purpose its upper end is chamfered off to allow the plunger to enter easily into the holes.

A treadle 166 is provided on the machine which is connected by means of a rod 168 with an arm 170 mounted on a rotary pin 172 having a bearing in the member 16 and having secured to its other end a lever 174 carrying at one end a roll 176 which engages the head 142 of the plunger 134 and is adapted to be moved downwardly by the operation of the treadle to withdraw the plunger 134 from the hole 164 in the ratchet wheel 162 at the beginning of the operation of the machine. A spring 178 (Fig. 4) is connected between the end of the lever 174 and the frame to raise the front end of the lever and the treadle 166.

In the normal operation of the machine, before a fresh shoe is to be jacked the central valve 24 will be so positioned in the neck of the turret 12 that the exhaust passage 128 therein will be in communication with the pad which lies directly in front of the operator when he stands in proper position facing the machine while the inlet passage 124 will be in communication with the pad next on the left of that pad.

Assuming that it is desired to remove a shoe from the machine after treatment thereby and to substitute another therefor, the operator takes up a position facing the machine in front of the treadle aforesaid. The pad immediately in front of the operator in such position will already have been deflated and the operator may therefore throw back the stirrup 100 from over the shoe supporting arm 68, thereby freeing the treated shoe which remains on the deflated pad when the arm has been lifted. After having removed this shoe and substituted another therefor on the pad, the operator swings the arm 68 downwardly to a more or less horizontal position, taking care that the short conical last pin 80 engages in the pin hole of the last and that the pressure roll 92 engages the toe portion squarely. Thereafter he swings the stirrup 100 forwardly over the top of

the arm 68 until it binds upon the cammed upper edge of the latter to retain it in depressed position and press the shoe upon the pad. Having finished this shoe jacking operation, the operator 5 depresses the treadle, thereby withdrawing the plunger 134 from the hole 164 in the ratchet wheel 162 (where it will be at this time) and allowing the arm 132 secured to the central valve 24 to swing quickly to the right (i. e., in a coun- 10 terclockwise direction when viewed from above) under the action of its spring 150, thereby swinging the central valve 24 in the same direction. During this movement the turret 12 is held from moving with the valve 24 by means of a retaining pawl 179 mounted on the bracket 154 and engaging the teeth of the ratchet wheel 162. The swinging movement of the valve 24 and the arm 132 extends through sixty degrees until the plunger 134 comes into alignment with another 15 hole in the ratchet wheel. The said rotary movement of the valve 24 causes the exhaust passage 126 therein to come into line, at the end of the said movement, with the inlet port 118 for that pad which lies next to the one in front of the operator to the right thereof and the air from this pad (which during the normal operation of the machine will be inflated at this time) will therefore escape down the exhaust duct 128 and allow the pad to deflate. 20

While this swinging movement of the central valve 24 is taking place, the air supply passage (which it will be remembered is at thirty degrees to the exhaust passage) will come into line with the inlet port for the pad which is directly in front of the operator and on which he has just jacked a shoe. The inflation of this pad will thereupon commence when the valve has moved thirty degrees and will continue as the rotary movement of the valve continues due to the provision 25 of the horizontal groove 124. Thus at the end of the swinging movement just described (i. e., just after the treadle has been depressed) the shoe which has just been jacked will be subjected to pressure by the inflation of its pad while the pad to the right of that one will be deflating. If desired, the horizontal groove 124 may be omitted and the inlet and exhaust passages may comprise only radial ports arranged at sixty degrees to each other. 30

A short time after the central valve 24 has reached the end of said movement the operator releases the treadle. The action of releasing the treadle is arranged to cause the slide valve 160 (which partakes of the rotary movements of the central valve) to move to such a position that compressed air may pass out of the central duct 120 in the central valve 24 into the pipe 156 leading to the cylinder 148. For this purpose there is connected to the treadle 166 by a yieldingly extensible rod 180 a bell-crank lever 182 which, when the treadle is depressed, urges rearwardly a spring-pressed stop 184 located in the line of movement of the slide valve 160. Release of the treadle when the central valve 24 has reached 35 the end of its said swinging movement allows the said stop 184 to advance to engage and move the slide valve 160 toward the left from its initial position, causing admission of compressed air to the pipe line 156 and therefore to the cylinder 148 so that the piston 146 is forced along the cylinder, thereby turning the central valve 24 to the left (i. e., in a clockwise direction when viewed from above) and by reason of the engagement of the plunger 134 with a hole 164 in the ratchet wheel 162, causing the turret 12 to move with it. The 40 movement to the left of the turret 12 and valve 24 proceeds (against the action of the spring 150 secured to the arm 132) for sixty degrees until it is arrested by contact of the arm 132 with a leaf buffer spring 186, and the turret 12 and valve 24 remain together in this position until the treadle is depressed again for another operation. Simultaneously with the contact between the arm 132 and the leaf spring 186 a second stop 188 abuts against the slide valve 160 and moves it to cut off the communication between the pipe line 156 and the central duct 120 in the central valve 24 and to allow the compressed air in the cylinder 148 to pass away to exhaust. Each partial rotation of the turret 12 carries that pad which has last been inflated and on which a shoe has just been jacket away from in front of the operator to the left and simultaneously brings into position in front of him that pad which was next on his right and which has been deflated. Thus the operator does not have to turn the turret manually and can more easily concentrate his attention on jacking and unjacking the shoes. Owing to the fact that adjacent pads are simultaneously in communication respectively with the inlet and 45 exhaust passages in the central valve 24 during the rotary movement of the turret 12 and the valve 24 together and also when the turret is stationary it will be understood that there is ample time for the inflating and deflating operation to 50 be carried out effectively during the interval between the jacking of successive shoes. The deflation of the one pad and the inflation of its neighbor, both being brought about by the aforesaid anticlockwise movement of the valve 24, are, 55 as illustrated, allowed to continue as the valve and turret together move clockwise. 50

In order to ensure that a sole shall be laid as tightly as possible against the waist of a high-arch shoe, the illustrative machine may be provided with rubber waist pads 190 which are flat on their lower sides to rest upon the pneumatic pads 32 and are shaped on their upper faces to conform approximately to the longitudinal and transverse curvature of the shank of such a high-arch shoe and each pad may be inserted between a pneumatic pad and the waist of a shoe before the commencement of a sole laying operation. One waist pad is provided for each pneumatic pad, and each is secured to the outer end of the corresponding pneumatic pad carrying bed. Each pad carrying bed 34 supports on a horizontal pivot 192 at its outer end a pair of short links 194 which in turn are pivoted at 196 to the sides of a supporting frame 198 for the waist pad 190 and the latter may, by such an arrangement, be swung upwardly and over the end of the pneumatic pad 32 to lie upon the pneumatic pad in a position beneath the waist of a shoe or, if it is not desired to use the waist pad, it may be lifted away from the pneumatic pad and allowed to hang from the end of the bed in an inoperative position. 60

To ensure that the plunger 134 may have ample time to engage properly in a hole in the ratchet wheel 162 before the piston 146 is caused to travel along its cylinder to turn the turret 12, means may be provided for slowing down the initial movement of the piston along its cylinder. For this purpose the passage in the cylinder casting 148 leading from the pipe line 156 to the interior of the cylinder may be divided into two branches 200, 202 of different diameters of which the smaller 200 leads into the cylinder close against the end wall thereof and the larger 202 65 70

leads into the cylinder, say one quarter of its length away from the end wall. By such an arrangement the piston 146 will first of all be given a relatively slow motion which will increase to a relatively fast motion as the piston travels down the cylinder and uncovers the larger port.

Having thus described my invention, what I claim as new and desire to secure by Letters Patent of the United States is:

- 10 1. In a sole pressing machine, the combination of a carrier, a plurality of sole pressing pads mounted upon the carrier, means for holding shoes on the pads, and a single means independent of movement of the carrier for applying pressure to the sole of a shoe on one of the pads and for relieving pressure on the sole of a shoe on another of the pads simultaneously.
- 20 2. A sole pressing machine having, in combination, a rotatable turret, a plurality of pneumatic sole pressing pads mounted upon the turret, means for holding shoes on the pads, a movable valve, and means for moving the valve, while the turret is at rest, to admit air to one of the pads and to exhaust air from another of the pads simultaneously.
- 30 3. A sole pressing machine having, in combination, a turret, means for rotating the turret, a plurality of inflatable sole pressing pads mounted upon the turret, means for holding shoes on the pads, a rotary valve, and operator-controlled means for moving the valve, while the turret is at rest, to admit fluid to one of the pads and to exhaust fluid from another of the pads simultaneously.
- 35 4. In a sole pressing machine, the combination of a carrier, a plurality of pressing units mounted upon the carrier to be presented by movement of the carrier successively in work receiving position, and pressure controlling means operating while each unit is in said position for applying pressure to that unit and for relieving pressure from the unit next to be brought into work receiving position by movement of the carrier.
- 45 5. In a sole pressing machine, the combination of a carrier, a plurality of sole pressing units on the carrier, each comprising a shoe holding device and a sole engaging pad adapted to be dilated by fluid pressure to apply pressure to a shoe bottom, and means operating without movement of the carrier from its work-receiving position for applying fluid pressure to dilate one of the pads while the carrier is at rest and for relieving the pressure from another adjacent pad to which pressure has previously been applied.
- 55 6. In a sole pressing machine, a rotary turret, a plurality of shoe holding and sole pressing devices mounted on the turret, a rotatable member about which the turret rotates, means for rotating the turret in one direction, and means for rotating said member in the opposite direction to cause pressure to be applied to a shoe in one pressing device and pressure to be relieved from a shoe in another pressing device.
- 65 7. In a sole pressing machine, the combination of a turret, a plurality of pneumatic pads carried by the turret, a plurality of shoe holding devices cooperating with the pads to hold shoes thereon, and means for supplying air to each of said pads in turn comprising a rotary valve located centrally of the turret and operating when turned relatively to the turret to admit air to one of the pads.
- 75 8. In a sole pressing machine, the combination of a turret, a plurality of pneumatic pads carried by the turret, a plurality of shoe holding devices

cooperating with the pads to hold shoes thereon, means for supplying air to each of said pads in turn comprising a valve located centrally of the turret and operating when turned relatively to the turret to admit air to one of the pads, spring means under initial tension for operating the valve, and operator controlled means for releasing the spring means.

9. In a sole pressing machine, the combination of a turret, a plurality of pneumatic pads carried by the turret, a plurality of shoe holding devices cooperating with the pads to hold shoes thereon, and means for supplying air to each of said pads in turn comprising a valve located centrally of the turret and operating when turned relatively to the turret to admit air to one of the pads and to exhaust air from an adjacent pad.

10. In a sole pressing machine, the combination of a turret, a plurality of pneumatic pads carried by the turret, a plurality of shoe holding devices cooperating with the pads to hold shoes thereon, means for conducting air to each of said pads in turn comprising a valve located centrally of the turret and operating when rotated relatively to the turret to admit air to one of the pads and exhaust air from an adjacent pad.

100

11. In a sole pressing machine, the combination of a turret, a plurality of pneumatic pads carried by the turret, a plurality of shoe holding devices cooperating with the pads to hold shoes thereon, means for supplying air to each of said pads in turn comprising a valve located centrally of the turret and operating when turned relatively to the turret to admit air to one of the pads, spring means under initial tension for operating the valve, operator controlled means for releasing the spring means, and means operated by rotation of the turret for restoring the initial tension of the spring means.

110

12. In a sole pressing machine, the combination of a turret, a plurality of sole pressing pads mounted on the turret, means for holding shoes on the pads, means for rotating the turret, and means including a rotary valve operable relatively to the turret while the turret is at rest for causing pressure to be applied to the sole of a shoe on one of the pads and pressure to be relieved from the sole of a shoe on another of the pads simultaneously.

120

13. In a sole pressing machine, the combination of a turret, a plurality of sole pressing pads mounted on the turret, means for holding shoes on the pads, means for rotating the turret, and pressure controlling means operable while the turret is at rest for causing pressure to be applied to the sole of a shoe on one of the pads and pressure to be relieved from the sole of a shoe on another of the pads, rotation of the turret acting to restore said pressure controlling means to its initial position.

130

14. In a sole pressing machine, the combination of a turret, a plurality of pressing units mounted on the turret to be presented by rotation of the turret successively in shoe receiving position, a spring, and pressure controlling means operated by said spring while each unit is in shoe receiving position to cause pressure to be applied to that unit and to relieve pressure from the unit next to be brought into shoe receiving position by movement of the turret.

145

15. In a sole pressing machine, the combina-

- tion of a turret, a plurality of pressing units mounted on the turret to be presented by rotation of the turret successively in shoe receiving position, a spring, pressure controlling means operated by said spring while each unit is in shoe receiving position to cause pressure to be applied to that unit and for relieving pressure from the unit next to be brought into shoe receiving position by movement of the turret, and 5 means operated by rotation of the turret for retensioning the spring. 80
16. In a sole pressing machine, the combination of a turret, a plurality of sole pressing units on the turret each comprising a shoe holding device and a sole engaging pad adapted to be dilated by fluid pressure to apply pressure to a shoe bottom, operator controlled means for causing dilation of one of the pads prior to movement of the turret, means acting during rotation of 15 the turret for relieving the pressure from an adjacent pad which has previously been dilated, and means for rotating the turret. 90
17. In a sole pressing machine, the combination of a turret, a plurality of pneumatic pads carried by the turret, a plurality of shoe holding devices cooperating with the pads to hold shoes thereon, a valve located centrally of the turret for rotation about the same axis as the turret, means for rotating the valve and turret in one direction, and means for rotating the valve reversely to the direction of rotation of the turret to cause 20 the valve to admit air to one of the pads and permit exhaustion of air from an adjacent pad. 95
18. In a sole pressing machine, the combination of a turret, a plurality of pneumatic pads carried by the turret, a plurality of shoe holding devices cooperating with the pads to hold shoes thereon, a valve located centrally of the turret for rotation about the same axis as the turret, means for rotating the turret, a spring for operating the valve arranged to be placed under tension by rotation of the turret, means for releasing the spring to cause rotation of the valve, and means operated by rotation of the turret, for restoring the valve to initial position and for re-tensioning the spring. 100
19. In a sole pressing machine, the combination of a turret, a plurality of pneumatic pads carried by the turret, means for holding a shoe upon each of the pads, power-operated means for rotating the turret, a rotary valve having its axis coincident with that of the turret, means for turning the valve in the same direction as the turret when the turret is rotated and for storing 50 energy reversely to move the valve, and operator controlled means for releasing said energy to cause the valve to be reversely moved while the turret is at rest to cause admission of air to one of the pads and exhaustion of air from an adjacent pad. 105
20. In a sole pressing machine, the combination of a turret, a plurality of pneumatic pads carried by the turret, means for holding a shoe upon each of the pads, a rotary valve having its axis coincident with that of the turret, means for turning the valve prior to movement of the turret to cause admission of air to one of the pads and exhaustion of air from an adjacent pad, said valve being constructed and arranged to admit 55 air to the empty pad before it exhausts air from the adjacent pad, and means for thereafter moving the turret. 110
21. In a sole pressing machine, the combination of a turret, a plurality of pneumatic sole pressing devices on the turret, means for transmitting compressed air for operating said pressing devices, means for admitting air to one of said pressing devices and exhausting air from another of said pressing devices, means for rotating the turret, and a single controlling member which, upon one movement, causes one pressing device to be inflated and another deflated and upon another movement causes the turret to be rotated. 85
22. In a sole pressing machine, the combination of a turret, a plurality of pneumatic sole pressing devices on the turret, means for transmitting compressed air for operating said pressing devices, means for admitting air to one of said pressing devices and exhausting air from another of said pressing devices, means for rotating the turret, and a treadle which, upon depression, causes one pressing device to be inflated and another deflated and upon release causes the turret to be rotated. 90
23. In a sole pressing machine, the combination of a turret, a plurality of pneumatic sole pressing pads mounted upon the turret, shoe holding means for holding shoes upon the pads, a rotary air valve having its axis of rotation coincident with that of the turret, a spring for rotating the air valve in one direction, power-operated means for moving the valve in the opposite direction and for simultaneously rotating the turret, and operator controlled means for releasing the valve to the action of the spring to rotate the valve reversely to the direction of rotation of the turret, said valve then acting to admit air to one of the pads and to exhaust air from another of the pads. 100
24. In a sole pressing machine, the combination of a turret, a plurality of pneumatic pads carried by the turret, means for holding a shoe upon each of the pads, a rotary valve having its axis coincident with that of the turret, and means for turning the valve while the turret is at rest to cause admission of air to one of the pads and exhaustion of air from an adjacent pad, said valve acting to admit air to one of the pads and later to exhaust air from an adjacent pad while continuing to supply air to the pad being filled. 105
25. In a sole pressing machine, a rotary turret, a plurality of shoe holding and sole pressing devices mounted on the turret, a rotatable member about which the turret rotates, means for rotating the turret in one direction to bring the pressing devices successively into work receiving position, and means for rotating said member in a direction opposite to the direction of rotation of the turret to cause pressure to be applied to a shoe in one of said pressing devices and pressure to be relieved from a shoe in another of said devices. 115
26. In a sole pressing machine, the combination of a turret, a series of pneumatic pads on the turret, a source of supply of compressed air, a rotary valve for controlling the admission of air to the pads and the exhaust of air therefrom, means for rotating the turret and valve together while air is being supplied to one pad and exhausted from another and to store energy reversely to move the valve, and operator controlled means for releasing the valve to permit it to rotate reversely to supply air to a previously exhausted pad and to exhaust a previously filled pad. 120
27. In a sole pressing machine, the combination of a turret, a series of pneumatic pads on the turret, a source of supply of compressed air, a rotary valve for controlling the admission of air 130
- 75

to the pads and the exhaust of air therefrom, and means for rotating the turret and valve together while air is being supplied to one pad and exhausted from another.

5 28. In a sole pressing machine, the combination of a turret, a plurality of pneumatic sole pressing pads mounted upon the turret, shoe holding means for holding shoes upon the pads, a rotary air valve having its axis of rotation coincident 80 with that of the turret, a spring for rotating the air valve in one direction, power-operated means for moving the valve in the opposite direction and for simultaneously rotating the turret, and a treadle, depression of which releases the valve to 85 10 the action of the spring to rotate the valve reversely to the direction of rotation of the turret, said valve acting to admit air to one of the pads and to exhaust air from another of the pads.

29. In a sole pressing machine, the combination 20 of a turret, a series of pneumatic pads on the turret, a source of supply of compressed air, a rotary valve for controlling the admission of air to the pads and the exhaust of air therefrom, means for rotating the turret and valve together while 25 air is being supplied to one pad and exhausted from another and to store energy reversely to move the pad, treadle operated means for releasing the valve to permit it to rotate reversely, to supply air to a previously exhausted pad and to 30 exhaust a previously filled pad, and treadle controlled means for causing the turret and valve to be rotated together.

30. In a sole pressing machine, the combination 35 of a turret, a plurality of sole pressing units on the turret each comprising a shoe holding device and a sole engaging pad adapted to be dilated by fluid pressure to apply pressure to a shoe bottom, an oscillating arm, a plunger on the arm normally engaging the turret, operator controlled 40 means for releasing the plunger from the turret, a spring for operating the arm when so released, and fluid pressure operated means for moving the arm against the spring and rotating the turret.

31. In a sole pressing machine, the combination 45 of a turret, a plurality of sole pressing units on the turret each comprising a shoe holding device and a sole engaging pad adapted to be dilated by fluid pressure to apply pressure to a shoe bottom, an oscillating arm, a plunger on the arm normally 50 engaging the turret, operator controlled means for releasing the plunger from the turret, a spring for operating the arm when so released, fluid pressure operated means for moving the arm against the spring and rotating the turret, and means for causing the initial movement of 55 the arm to be slow and its subsequent movement rapid.

32. In a sole pressing machine, the combination 60 of a turret, a plurality of sole pressing units on the turret each comprising a shoe holding device and a sole engaging pad adapted to be dilated by fluid pressure to apply pressure to a shoe bottom, an oscillating arm, a plunger on the arm normally 65 engaging the turret, manually operated means acting when moved in one direction to release the plunger from the turret, a spring for operating the arm when so released, fluid pressure operated means for moving the arm against the spring and rotating the turret, and means operated by return movement of the manually operated means to cause operation of the fluid pressure operated means.

33. In a sole pressing machine, the combination 70 of a shoe support having a pad thereon adapted to conform substantially to the shape of

the shoe bottom, a pivoted arm adapted to be swung toward a shoe on the pad to press the shoe against the pad and having a cam surface on its upper side, and a stirrup extending over the arm and pivoted to the pad substantially at the longitudinal center thereof, said stirrup being adapted to be swung along the arm away from the pivot of the arm to force the arm in pressing position against the shoe. 80

34. In a sole pressing machine, the combination of a shoe supporting bed having a pad thereon adapted to conform substantially to the shape of a shoe bottom, a member arranged for movement toward a shoe on the bed to press the shoe against the bed, said member having a cam surface on its outer face, and a stirrup extending over the member and pivoted to the bed substantially at the longitudinal center thereof, said stirrup being adapted to swing along the member and by engagement with said cam surface to force the member into pressing position against the shoe. 85

35. In a sole pressing machine, the combination of a shoe supporting bed having a pad thereon adapted to conform substantially to the shape 90 of a shoe bottom, an arm adapted to be swung toward the shoe on the bed to press it against the pad, and a stirrup extending at all times over the arm and pivoted to the bed substantially at the longitudinal center thereof, said stirrup being 95 adapted to swing rearwardly of the shoe along the arm to retain the arm in pressing position against the shoe. 100

36. In a sole pressing machine, the combination of a shoe supporting bed adapted to conform 110 substantially to the shape of a shoe bottom, an arm pivoted adjacent to the toe end of the bed and adapted to swing toward a shoe to press it against the bed, and a stirrup extending over said arm and pivoted to the bed beneath the 115 shank portion of the shoe, said arm having a stirrup engaging surface eccentric to the path of the stirrup to cause the arm to be clamped against the shoe by swinging movement of the stirrup. 120

37. In a sole pressing machine, the combination of a shoe supporting bed adapted to conform 125 substantially to the shape of the shoe bottom, an arm pivoted adjacent to the toe end of the bed and adapted to be swung toward a shoe to press it against the bed, a spring for swinging the arm 130 away from the shoe, and a stirrup extending over said arm and pivoted to the bed, said arm having a stirrup engaging surface eccentric to the path of the stirrup to cause the arm to be clamped against the shoe by swinging movement of the stirrup along the eccentric surface of said arm. 135

38. In a sole pressing machine, the combination of a shoe supporting bed adapted to conform 140 substantially to the shape of the shoe bottom, an arm adapted to swing toward a shoe to press it against the bed, and a stirrup extending over said arm and pivoted to the bed midway of the length of the bed, said arm having a stirrup engaging surface eccentric to the path of the stirrup to cause the arm to be clamped against the shoe by 145 swinging movement of the stirrup toward the rear end of the shoe.

39. In a sole pressing machine, the combination of a shoe supporting bed, means for supporting the bed at two points transversely thereof 145 near the middle of the length of the bed, and a third support for said bed located near one end of the bed, said support being yielding to permit tipping of the bed on the two-point support.

40. In a sole pressing machine, the combina- 150

- tion of a shoe supporting bed, means for supporting the bed at two points transversely thereof near the middle of the length of the bed, and a third support for said bed located near one end of the bed, said support comprising opposed springs arranged to permit tipping of the bed on the two-point support in either direction. 5
41. In a sole pressing machine, the combination of a shoe supporting bed, stems for supporting the bed at two points transversely thereof near the middle of the length of the bed, means for adjusting said stems relatively to each other, and a third support for said bed located near one end of the bed. 10
42. In a sole pressing machine, the combination of a shoe supporting bed, a dilatable pad upon the bed, means for holding a shoe on the pad, a separate shank pad having its shoe engaging surface shaped complementally to that of the shank portion of the shoe and adapted directly to engage the shank portion only of the shoe, and means for holding the shank pad upon the dilatable pad. 15
43. In a sole pressing machine, the combination of a shoe supporting bed, a dilatable pad upon the bed, means for holding a shoe on the pad, a separate shank pad having its shoe engaging surface shaped complementally to that of the shank portion of the shoe, and links connecting said pad to the bed to locate it properly on the bed and permitting it to be moved out of operative position without disconnecting it from the bed when its use is not desired. 20
44. A sole pressing machine having, in combination, a turret, a plurality of fluid-operated pads on the turret, means for rotating the turret to bring the pads successively into a single operating position, operator-controlled means for causing fluid to enter the pad that is in operating position prior to movement of the turret, and means for continuing the supply of fluid to that pad during movement of the turret to bring another pad into operating position. 25
45. A sole pressing machine having, in combination, a turret, a plurality of fluid operated pads on the turret, means for rotating the turret to bring the pads successively into a single operating position, operator-controlled means for exhausting fluid from the pad that is next to the operating position prior to movement of the turret to bring that pad into operating position, and means for continuing the exhaust of that pad during its movement into operating position. 30
46. A sole pressing machine having, in combination, a turret, a plurality of fluid-operated pads on the turret, means for rotating the turret to bring the pads successively into a single operating position, a valve movable in one direction for admitting fluid to the pad that is in operating position without moving the pad therefrom, said valve also exhausting fluid from the next succeeding pad, and means for moving the valve in the opposite direction during rotation of the turret to maintain said fluid admission and exhaust with relation to the pads during rotation of the turret. 35
47. In a sole pressing machine, the combination of a turret, a plurality of fluid-operated pressing devices on the turret, means for transmitting fluid under pressure for operating said pressing devices, means for admitting fluid to one of said pressing devices, means for rotating the turret, and a single controlling member which, upon one movement, causes fluid under pressure to be admitted to one of the pressing devices and upon another movement causes the turret to be rotated. 40
48. A sole pressing machine having, in combination, a turret, a plurality of fluid-operated pads on the turret, means for rotating the turret to bring the pads successively into a single operating position, means for exhausting fluid from the pad that is next to the operating position prior to movement of the turret to bring that pad into operating position, and means for maintaining the exhaust of that pad open during its movement into operating position. 45
49. In a sole pressing machine, the combination of a turret, a plurality of fluid-operated pressing devices on the turret, means for transmitting fluid under pressure for operating said pressing devices, means for admitting fluid to one of said pressing devices, means for rotating the turret, and a controlling member movement of which causes fluid under pressure to flow to one of the pressing devices and later causes the turret to be rotated. 50
50. In a sole pressing machine, the combination of a turret mounted for rotation about a vertical axis, a plurality of pressing units mounted upon the turret to be presented by rotation of the turret successively in a predetermined work-receiving position, each of said units including an inflatable pad, and means for deflating each pad prior to its arrival at said predetermined work-receiving position and for inflating the pad while it is in said position. 55
51. In a sole pressing machine, the combination of a movable carrier, a plurality of pressing units mounted upon the carrier to be presented by movement of the carrier successively in a predetermined work-receiving position, each of said units including an inflatable pad, means for causing inflation of a pad while in said predetermined work-receiving position, and means operated automatically by said means for causing deflation of another pad. 60
52. In a sole pressing machine, the combination of a turret mounted for rotation about a vertical axis, a plurality of pressing units mounted upon the turret to be presented by rotation of the turret successively in a predetermined work-receiving position, each of said units including an inflatable pad, means for causing inflation of a pad while it is in said predetermined work-receiving position and for causing deflation of another pad, and means for rotating the turret while continuing the inflation of the pad which is leaving the predetermined work-receiving position and while continuing the deflation of the other pad. 65
53. In a sole pressing machine, the combination of a turret mounted for rotation about a vertical axis, a plurality of pads mounted on the turret, a plurality of shoe-engaging devices one for each of the pads, means operating independently of rotation of the turret for relatively operating each pad and its shoe-engaging device in turn to apply pressure to a shoe, and means operating without special attention on the part of the operator for relieving said pressure when the turret has nearly completed a rotation. 70
54. In a sole pressing machine, the combination of a turret mounted for rotation about a vertical axis, a plurality of pads mounted on the turret, a plurality of shoe-engaging devices one for each of the pads, fluid-operated means for pressing each pad and shoe-engaging device toward each other to apply pressure to a shoe, 75

- manually controlled means for causing fluid to be admitted to the fluid-operated means of one pad while the turret is at rest, and means operated by said manually operated means for causing pressure to be relieved from a shoe on another pad. 80
55. In a sole pressing machine, the combination of a carrier, a plurality of pressing units on the carrier to be presented by movement of the carrier successively in work-receiving position, means for intermittently moving the carrier, and pressure-controlling means operable while each unit is in work-receiving position for causing pressure to be applied to that unit which is in work-receiving position and for causing pressure to be relieved from the unit next to be brought into work-receiving position by movement of the carrier. 85
56. In a sole pressing machine, the combination of a carrier, means for intermittently moving the carrier step by step, a plurality of pads on the carrier, a plurality of holding means for pressing shoes on the pads, operator-controlled means independent of movement of the carrier for causing relative movement of one shoe-holding device and its pad thereby applying pressure to a shoe on that pad, means for moving the carrier one step while said pressure is being applied, and means for simultaneously relieving pressure on another shoe. 90
57. In a sole pressing machine, the combination of a turret arranged for rotation on a vertical axis, means for intermittently rotating the turret step by step, a plurality of pads on the turret, means for pressing shoes down upon the respective pads, and operator-controlled means for causing pressure to be applied to a shoe on a pad at one operating station of the turret and for substantially simultaneously relieving pressure on a shoe on a pad at another station. 95
58. In a sole pressing machine, the combination of a carrier, a plurality of pads on the carrier, means for intermittently moving the carrier step by step to present the pads in turn at an operating station, means for holding shoes on the respective pads, and operator-controlled means for causing relative movement of the holding means and the pad at the operating station while the carrier is at rest to apply pressure to a shoe on that pad, said means acting simultaneously to relieve pressure on the shoe on the pad next to be brought to the operating station by movement of the carrier. 100
59. In a sole pressing machine, the combination of a carrier, a plurality of pressing units on the carrier to be presented by movement of the carrier successively in work-receiving position, means for intermittently moving the carrier, pressure-controlling means operable while each unit is in work-receiving position for causing pressure to be applied to that unit which is in work-receiving position and for causing pressure to be relieved from the unit next to be brought into work-receiving position by movement of the carrier, and means for reversely moving said pressure-controlling means during movement of the carrier to continue the application of pressure to the unit leaving the work-receiving position. 110
60. In a sole pressing machine, the combination of a turret mounted for rotation about a vertical axis, a plurality of inflatable pads on the turret, a plurality of shoe-engaging devices one for each of the pads, a fluid-pressure-controlling valve movable while the turret is at rest for causing inflation of one of the pads and for relieving pressure on another pad, and means for reversely moving the valve during rotation of the turret to maintain the supply of fluid to the pad that is being filled and to continue the exhaustion of the pad being deflated. 115
61. In a sole pressing machine, the combination of a turret, a plurality of pneumatic pads carried by the turret, a plurality of shoe-holding devices cooperating with the pads to hold shoes thereon, means for supplying air to each of said pads in turn comprising a valve operating when turned relatively to the turret to admit air to one of the pads, spring-controlled means under initial tension for turning the valve to admit air to the pad, and operator-controlled means for releasing the spring means. 120
62. In a sole pressing machine, the combination of a turret, a plurality of inflatable pads carried by the turret, a plurality of shoe-holding devices cooperating with the pads to hold shoes thereon, and means for supplying fluid to each of said pads in turn comprising a valve operable independently of movement of the turret for causing admission of fluid to one of the pads and exit of fluid from an adjacent pad. 125
63. In a sole pressing machine, the combination of a turret, a plurality of inflatable pads carried by the turret, a plurality of shoe-holding devices cooperating with the pads to hold shoes thereon, means for supplying fluid to each of said pads in turn comprising valve means operable while the turret is at rest for causing admission of fluid to one of the pads and to cause another of the pads to be exhausted. 130
64. In a sole pressing machine, the combination of a turret, a plurality of inflatable pads carried by the turret, a plurality of shoe holding devices cooperating with the pads to hold shoes thereon, means for conducting fluid to each of said pads in turn comprising a valve operating to admit fluid to one of the pads and to exhaust fluid from an adjacent pad, a spring for rotating the valve relatively to the turret, means operated by the turret for resetting the valve, and an operator-controlled latch for holding the spring under tension and releasing it. 135
65. In a sole pressing machine, the combination of a turret, a plurality of inflatable pads carried by the turret, a plurality of shoe-holding devices cooperating with the pads to hold shoes thereon, means for supplying fluid to each of said pads in turn comprising a valve operating to admit fluid to one of the pads, spring means under initial tension for operating the valve, operator-controlled means for releasing the spring means, and means operated by rotation of the turret for restoring the initial tension of the spring means. 140
66. In a sole pressing machine, the combination of a turret, a plurality of sole pressing means on the turret, each comprising a shoe-holding device and a sole-engaging pad, means for relatively operating each shoe-holding device and sole-engaging pad to apply pressure to the shoe bottom, operator-controlled means for causing pressure to be applied to a shoe on one of the pads prior to movement of the turret, means acting during the rotation of the turret for relieving pressure on a shoe on an adjacent pad, and means for rotating the turret. 145
67. In a sole pressing machine, the combination of a turret, a plurality of inflatable pads carried by the turret, means for holding a shoe on each of said pads, power-operated means for rotating the turret, a rotary valve for controlling the passage of fluid into and out of the pads, 150

- means for turning the valve in one direction when the turret is rotated and for storing energy to effect reverse movement of the valve, and operator-controlled means for releasing the energy 5 to cause the valve to be reversely moved while the turret is at rest to admit air to one of the pads and to exhaust air from an adjacent pad.
68. In a sole pressing machine, the combination of a turret, a plurality of fluid-operated sole 10 pressing devices on the turret, means for transmitting fluid under pressure for operating said pressing devices, means for admitting fluid to one of said pressing devices, means for exhausting fluid from another of said pressing devices, means 15 for rotating the turret, and a treadle which upon depression causes one pressing device to be operated to apply pressure to the shoe and pressure to be relieved from a shoe in another pressing device in which the shoe is under pressure.
69. In a sole pressing machine, the combination of a turret, a plurality of inflatable pads on the 20 turret, means for transmitting fluid under pressure to inflate said pads, means for admitting fluid to one of said pads and exhausting fluid from another of said pads, means for rotating the 25 turret, and a treadle which upon depression causes
- one pad to be inflated and another deflated and upon release causes the turret to be rotated.
70. In a sole pressing machine, the combination of a turret, a plurality of inflatable pads carried by the turret, means for holding a shoe upon 80 each of the pads, a rotary valve, means for turning the valve while the turret is at rest to cause admission of air to one of the pads and exhaustion of air from an adjacent pad, said valve acting to admit air to one of the pads and later 85 to exhaust air from an adjacent pad while continuing to supply air to the pad being filled, and means for continuing the supply of air to the pad being filled and the exhaustion of air from the adjacent pad during the rotation of the 90 turret.
71. In a sole pressing machine, a rotary turret, a plurality of shoe pressing devices mounted on the turret, means for rotating the turret in one direction to bring the pressing devices successively into work-receiving position, a pressure-controlling member, and means for operating said member to cause pressure to be applied to a shoe in one of said pressing devices and pressure to be relieved from another of said devices. 95
